UNITED STATES PATENT OFFICE.

RICHARD MILLER, OF APPLETON, WISCONSIN.

BOWLING-PIN.

1,257,377.

Specification of Letters Patent. Patented Feb. 26, 1918.

Application filed February 28, 1917. Serial No. 151,423.

To all whom it may concern:

Be it known that I, RICHARD MILLER, citizen of the United States, residing at Appleton, county of Outagamie, and State of Wisconsin, have invented new and useful Improvements in Bowling-Pins, of which the following is a specification.

My invention relates to improvements in bowling pins and processes of making the same, this application being a continuation in part of a former application filed by me September 21, 1916, Serial No. 121,865.

The object of my invention is to provide means for utilizing short maple slab sections constituting a by-product of other articles of manufacture, whereby such slab sections may be combined to form a balanced bowling pin of peculiar and unusual strength and durability conformable in all cases to a predetermined standard of weight.

I have found that wooden blocks substantially the same in appearance differ greatly in weight. Therefore it is not only necessary to select slabs or members of substantially uniform weight with which to construct the body of any given bowling pin but it is also necessary, in order to provide sets of pins each of which conforms to a certain standard of weight, to devise means whereby in the assembly of the pieces or sections, the central cavity may be formed which increases or decreases in size in the different pins in inverse proportion to the weight of the material. The particular manner in which I assemble these several sections or members in my improved pin enables me to regulate the size of the cavity during the operation of assembling the final section or member in position, all of the other members having been previously associated and firmly glued together.

In the drawings—

Figure 1 is a perspective view of one of the slab sections from which my improved bowling pin is made.

Fig. 2 is a vertical sectional view of a bowling pin having a body formed of relatively light material constructed in accordance with my invention with dotted lines indicating the original contour of the sections or pieces of which it is composed.

Fig. 3 is a similar view partly in elevation illustrating my improved pin as con-

structed of relatively heavy material in the body portion.

Figs. 4 and 5 are cross sections drawn generally on lines 4—4, 5—5 respectively of Fig. 2, and showing slight modifications.

Like parts are identified by the same reference characters throughout the several views.

A pair of slab sections A are first tested for uniformity in weight. I then face off their inner surfaces and glue them together as indicated at B in Fig. 2. A socket C is then formed by boring a hole in one end of the block, composed of the two sections A,—A. A handle section D is then formed with a cylindrical end portion E adapted to closely fit the socket C. This cylindrical portion E is then driven into the socket to a position in which the pin will conform to a predetermined standard of weight. For example, where the sections A are of minimum weight, the shank portion E of the handle will be driven substantially to the bottom of the socket C as illustrated in Fig. 2. But if the sections A,—A are heavy, the shank section E will be only driven into the socket leaving a cavity of considerable size between the lower end of the shank E and the bottom C' of the socket as shown in Fig. 3.

The contacting surfaces of the shank E or the walls of the socket will be covered with glue before the shank is driven into position, the shank being fully adjusted before allowing the glue to set or dry. The upper ends of the handle D will then be cut so as to conform the pin to a standard head, after which the pins may be turned in a lathe to the desired contour.

It will be observed that, in Figs. 2 and 3, the completed pin comprises three pieces or sections, two of which comprise the body of the pin while the third forms the handle or upper portion. If desired, dowel pins F, (Figs. 4 and 5), may be employed to more securely connect the sections A,—A with each other, but where the sections are properly glued, these pins F will not be necessary.

Where the slabs are thin, the body may be composed of three sections as shown in Fig. 5, in which two slab sections A',—A' are combined with a third or filler section G.

The filler section will be used in cases where the slabs are not thick enough to enable me to form a pin from two slabs meeting at the center or in a plane substantially intersecting the center of the pin.

- Where a filler section G is employed, said section will preferably be made narrow enough so that the handle section D will extend entirely across it and securely engage 10 in the slab sections A',—A' as indicated at e in Fig. 5. Therefore it is obvious that the handle section shank E will cross the joint formed between the slab sections A' and the filler sections G. This is not essential for 15 the reason that the glue will ordinarily hold the sections together so that splitting will never occur in the meeting surfaces, the glue having greater resistance than the fiber of the wood.
- 20 The slabs constitute the white wood of the maple tree from which they are cut and this makes them particularly valuable for my purposes since the white wood of a maple tree not only makes the pin of neater appearance, but it also resists impacts without 25 splitting better than the heart of the tree. My improvement, however, enables me to employ for the upper portion or handle, wood from the heart of the tree or wood of 30 different varieties, thereby producing pins the bodies of which are white and the upper portions or handles colored to suit the requirements of the user. The heart wood of a maple tree is a reddish tinge which 35 contrasts very neatly with the white wood of the body portion. I preferably make the upper or neck and head portions of the pin from a separate piece, for the reason that these portions being small in cross section, 40 a considerable quantity of the white wood would be wasted if the entire pin were made from two pieces or slabs instead of three. By making the pin in three pieces and utilizing other material for the neck and head 45 portions of the pin, I am enabled to economize in the use of the white wood to the fullest possible extent.

It will be understood that inasmuch as the handle section is preferably driven into 50 the socket C preparatory to shaping the bowling pin in the lathe, it will be necessary to determine the weight of the various sections proportionately to their volume before gluing them together. This, however, can 55 be very easily done, since only approximate uniformity in weight is required. The size of the block may be determined either by measurement or otherwise, and the weight for any given unit of volume may thus be 60 easily computed with sufficient exactness to suit the requirements.

I claim:—

1. A bowling pin including a body portion composed of two sections glued together, 65 in combination with neck and head portions

formed in one piece with the neck portion socketed in the upper end of the body portion, the socket in the body portion extending vertically therein and terminating above the lower ends of said sections, whereby the 70 lower ends of the sections may have flat bearing areas glued together from one side of the pin to the other.

2. A bowling pin having in combination a body portion formed in two sections having rigidly connected meeting faces and provided with a socket at the upper end of the body portion extending vertically into the body across the joint between said two sections, and an upper portion provided 80 with a tenon fitting said socket and rigidly connected with the walls thereof.

3. A bowling pin having in combination a plurality of body sections glued together in a vertical plane, and an upper section 85 provided with a cylindrical lower end portion socketed in the upper end of the body and glued to a plurality of body sections.

4. A bowling pin having in combination a plurality of body sections glued together 90 in a vertical plane, and an upper section provided with a cylindrical lower end portion socketed in the upper end of the body and glued to a plurality of body sections, the socket in the body extending across the 95 joint between the meeting faces of the sections.

5. A set of bowling pins, each including a body portion composed of a plurality of sections glued together in a vertical plane 100 in combination with a handle section socketed in the upper end of the body portion, said body portion having a socket of sufficient length to receive the handle section at a depth suitable to conform the pin to a predetermined standard of weight, and the handle sections of the different pins being disposed in said sockets at different depths.

6. A set of bowling pins each including a body portion composed of a plurality of sections glued together in a vertical plane and having a socket extending into the body portion from the upper end and crossing the joint between the two sections, in combination with a handle portion provided 115 with a shank fitted to said socket and extending to a sufficient depth therein to conform the body portion to a predetermined standard of weight, said pins each having its handle shank of a length and depth within the socket equal to that required to conform the pin to a predetermined standard to which each of the other pins conforms.

7. A set of bowling pins, each including the combination of a body portion composed 125 of two sections substantially alike in weight for equal volumes of material, said sections being glued together in a vertical plane and having a socket at its upper end through which said vertical plane extends, and a 130

handle portion provided with a shank fitted to said socket and extending into the latter to a sufficient depth to conform the pin to a standard weight, said pins each having its handle shank of a length and depth within the socket equal to that required to conform the pin to a predetermined standard to which each of the other pins conforms.

8. The process of manufacturing bowling pins conforming to a predetermined standard of weight, consisting; first, in preparing the body portion of the pin and forming a socket therein extending downwardly from its upper end; second, in forming a handle 15 with a shank portion adapted to fit said socket; and third, in driving the handle shank into said socket and securing the same therein at a depth sufficient to conform the pin to a required standard of weight.

9. The process of manufacturing bowling pins consisting; first, in selecting a plurality of body sections having substantially uniform weight in proportion to volume; second, facing said sections and gluing them together; third, forming a socket in one end 25 of the block produced by gluing said sections together; fourth, forming a handle portion with a shank adapted to fit said socket; fifth, securing said shank in the socket at a sufficient depth to conform the pin to the 30 required standard of weight; sixth, shaping the stock in a lathe to the desired contour.

In testimony whereof I affix my signature in the presence of two witnesses.

RICHARD MILLER.
